US0D1063835S

(12) **United States Design Patent** (10) **Patent No.:** **US D1,063,835 S**
(45) **Date of Patent:** **** Feb. 25, 2025**

(54) **POWER SOURCE**

(71) Applicant: **HENCA (HONG KONG) LIMITED**,
Kowloon (HK)

(72) Inventor: **Jinshan Chen**, Kowloon (HK)

(73) Assignee: **HENCA (HONG KONG) LIMITED**,
Kowloon (HK)

(**) Term: **15 Years**

(21) Appl. No.: **29/862,588**

(22) Filed: **Dec. 9, 2022**

(51) LOC (15) Cl. **13-02**

(52) U.S. Cl.

USPC **D13/103**

(57) **CLAIM**

The ornamental design for a power source as shown and described.

DESCRIPTION

FIG. 1 is a front, right and top perspective view of a power source, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is an enlarged view of detail 10 in FIG. 2.

The broken lines depict portions of the power source that form no part of the claimed design.

The dot-dash broken lines in FIGS. 1, 2, 9 and 10 depict the boundaries of the enlargements that form no part of the claimed design.

1 Claim, 10 Drawing Sheets
